To all whom it may concern:

Be it known that I, Abraham G. Feldman, a citizen of the United States, residing in Chicago, in the county of Cook, and State of Illinois, have invented a new, original, and ornamental Design for an Infant's Crib, of which the following is a specification, reference being had to the accompanying drawing forming part thereof, in which:

The single figure of the drawing is a perspective view taken from one end and somewhat to one side of an infant's crib embodying my new design, a mattress being shown in dotted lines.

It will be noted that the head end of the crib differs from the foot end at the top and bottom

portions of the head panel, which latter portion terminates at the mattress line.

I claim:

The ornamental design for an infant's crib, substantially as shown and described.
